Primary Examiner — Sheryl Lane*Assistant Examiner* — Ieisha N Price(74) **Attorney, Agent, or Firm** — Oyen Wiggs Green & Mutala LLP; Nicholas Garner(57) **CLAIM**

The ornamental design for a pipe thread protector, as shown and described.

DESCRIPTION

FIG. 1 is a top perspective view of a pipe thread protector;
 FIG. 2 is a bottom perspective view thereof;
 FIG. 3 is a right side elevational view thereof;
 FIG. 4 is a left side elevational view thereof;
 FIG. 5 is a front side elevational view thereof;
 FIG. 6 is a rear elevational view thereof;
 FIG. 7 is a top plan view thereof; and,
 FIG. 8 is a bottom plan view thereof.

The broken lines in the drawings illustrate portions of the pipe thread protector and form no part of the claimed design.
